WINDOW EQUIPMENT

Filed June 15, 1929

UNITED STATES PATENT OFFICE

CHARLES RAW, OF TOLEDO, OHIO

WINDOW EQUIPMENT

Application filed June 15, 1929. Serial No. 371,225.

My invention has for its object to provide an efficient means for maintaining a sash of a window tightly against the guiding frames or strips of the window when slidably moving the sash and when the sash is secured or locked in the position in which it is located. The invention also provides a lifting member located within the plane of the inside surface of the sash frame, whereby the outer sash may be located relative to the lower sash and the lifting member may pass the inner sash. It also affords a simple and convenient lifting member that may be attached to either or both sashes.

The invention may be contained in structures that vary in their details and, to illustrate a practical application of the invention, I have selected a window equipment means containing the invention as an example of the various embodiments of my invention, and shall describe it hereinafter. The structure selected is shown in the accompanying drawing.

Fig. 1 illustrates a perspective view of a window frame. Fig. 2 is an edge view of a sash. Fig. 3 is a view of a side of the frame. Fig. 4 is a view of a section of a latch. Fig. 5 is a view of a section of the latch taken on the plane of the line 5—5 indicated in Fig. 4. Fig. 6 is a view of a part of the sash having a roller. Fig. 7 is a view of a section taken on the plane of the line 7—7 indicated in Fig. 6. Fig. 8 is a front view of the window raising member. Fig. 9 is a side view of the window raising member.

The frame 1 is provided with the usual sashes 2 and 3 that are separated from each other and guided by the usual strips 4 in the manner well known in the art. The sashes are each provided with a pair of latches 7, and the window frame is provided with a plurality of strips 8, preferably of metal. The strips 8 are located in the channels formed between the guiding strips of the frame. A strip 8 is associated with each latch 7 and is provided with recesses 9 that are adapted to receive the inner end of the latch 7 at different points of location of the sashes.

The latches 7 are provided with curved

convex surfaces 12. A plane that passes through the inner and outer edges of the curved surface 12 is inclined to the longitudinal axis of the latch and to the surface of the strip 8 associated with the latch. The surface 12 is located on the side of the end of the latch that is located on the interior of the building. It is adapted to engage the edges 13 of the recesses 9 to press the sash outward against its associated guiding strips when the latch is pressed into the recess 9.

The latches 7 are spring pressed by means of the springs 15 that are located in slots 16 in which the screws or bolts 17 are located for securing the latches in slidable relation to the sashes with which the latches are associated. The latches 7 are preferably slidably supported in shells 18 that are mortised in the side of the sashes. They are secured not only by the screws 17 but also by the screws 19, which are located in the slots 20 to permit free movement of the latches 7 when actuated either manually or by the springs 15. Each latch may be provided with an annular finger member 22 whereby the latch may be withdrawn from the recesses 9 and the window raised and lowered.

In addition to the operation of the latches to press the sashes outwardly and tightly against the guiding frame, the sashes are also provided with the spring pressed rollers 25 which are supported in the slidable frames 26 for rotative movements relative to the frames 26. The frames 26 are slidably supported in the shells 27 and the frames 26 are spring pressed by means of the springs 28 located between the sides 29 and 30 of each frame 26 and its associated shell 27. The frames 26 are also held from outward movement beyond a given point by the screws 32 located in slots 33 formed in the side walls of the frames 26. The shells 27 are mortised in the edges of the sashes and are secured by means of the screws 31. The rollers 25 roll on the surface 35 of the strip 8 located at a right angle to the side of the strip having the recesses 9. The roller is located on the inside of the sash with which it is associated and so as to press the sash outward tightly against the outer guiding

strip of the frame and in the same direction that the curved surface 12 of the end of the latch operates to press the sash. Thus, in the form of construction shown, the roller and the latch are preferably spaced apart, whereby the sash will be tightly pressed against the outer strip and prevent weather from affecting the interior of the building. Any number of rollers may be located on each side of a sash. The number used will depend on the height of the sash.

The sashes may be provided with lifting members. The lifting member is particularly advantageous when secured to the upper sash whose lower edge, when the window is closed, is located on the outside of the upper edge of the lower sash. It has a finger member 40 that curves rearwardly from the body portion 41 of the lifting member substantially as shown in Figs. 8 and 9. The member 42 may be secured by means of screws that pass through the openings 43 formed in the body member 41 of the lifting member 42. In raising the sashes the thumb may be conveniently inserted beneath the curved finger member 40. To lower the window it may be pushed down by pressure on the upper side of the curved portion 40 of the lifting member.

30 I claim:

In a window equipment, a spring pressed latch having a sloping surface, the latch slidably supported in the sash, the frame of the window having a plurality of notches adapted to be engaged by the latch, the sloping surface adapted to engage one edge of the notch to press the sash outward against the guiding strip on the frame of the window, a shell for containing the latch, the latch having a slot, a pin supported in the shell and extending through the slot, a spring located intermediate the pin and the end of the slot for pressing the latch outward and towards the frame of the window, the latch comprising a bar entirely located within the thickness of the sash and having an eye located in a portion protruding inwardly from the sash frame for operating the latch, and a roller located in a position spaced from the latch and in the sash, a frame for rotatably supporting the roller, a shell for slidably supporting the frame, a spring located intermediate opposing sides of the shell and frame for pressing the roller outward with respect to the sash and inward with respect to the building in which the frame is located, the roller located near another corner of the sash and on the same side of the sash that the said latch is located on.

60 In witness whereof I have hereunto signed my name to this specification.

CHARLES RAW.
